UNITED STATES PATENT OFFICE.

FRANCIS D. MONTAGUE, OF HOPEDALE, MASSACHUSETTS, ASSIGNOR OF
ONE-HALF TO GEORGE DRAPER & SONS, OF SAME PLACE.

APPARATUS FOR DISTRIBUTING OIL ON THE SURFACE OF THE SEA.

SPECIFICATION forming part of Letters Patent No. 364,538, dated June 7, 1887.

Application filed January 29, 1887. Serial No. 225,886. (No model.)

To all whom it may concern:

Be it known that I, FRANCIS D. MONTAGUE, a citizen of the United States, residing at Hopedale, in the county of Worcester and State of Massachusetts, have invented a new and useful Improvement in Apparatus for Distributing Oil on the Surface of Troubled Seas, of which the following is a specification, reference being made to the accompanying drawings, 10 which form a part thereof.

The object of my invention is to provide an apparatus to be carried in life-boats and larger vessels, adapted to distribute a film of oil on troubled seas for the purpose of calming the 15 surface of the same and rendering it smooth in the roughest weather.

In carrying out my invention I use a tank partly filled with oil, an air-pump connected thereto for the purpose of forcing air under 20 pressure into said tank, and thereby forcing oil therefrom through one or more discharge-pipes extending from said tank over the bow or other portion of the vessel, whereby the oil is gradually distributed over the surface of 25 the water.

In the drawings, Figure 1 represents, in elevation, a surf life-boat; and Fig. 2, a plan of a larger vessel, both illustrating my invention. Fig. 3 is an enlarged detail view of the oil- 30 tank and air-pump connected, and Fig. 4 shows convenient forms of distributing nozzles.

Similar letters of reference indicate corresponding parts in all the figures.

35 A is a vessel, B an oil-tank placed therein at any convenient point, and C an air-pump connected to said tank by the tube a, whereby air may be forced into said oil-tank by said air-pump. The discharge-pipe b leads from 40 the oil-tank B, and is carried outside the vessel by a boom or otherwise, and terminates in a nozzle or distributor, c, preferably turned downward, in order to direct the stream of oil downward toward the surface of the water.

45 The discharge-pipe b may, if desired, be connected to the bottom of the tank B; but, as shown in the drawings, it is connected at the top of the tank to the internal tube, b', (shown in dotted lines,) which extends down close 50 to the bottom of the tank, as shown. It will be understood that the tank, which is airtight, is filled nearly full of oil—say up to the

line d, and the space above that line is occupied by air.

The mode of operation is as follows: Suppose it is desired to reach a wreck lying off shore through a rough surf. The surf-boat A, provided with the apparatus described, has a boom, D, thrust forward from the bow. Said boom carries the discharge-pipe b—in this case 60 preferably flexible—terminating in the nozzle c. The boat is launched, one man working the air-pump and forcing air into the tank B, and thus forcing the oil out through the discharge-pipe b and nozzle c. The oil thus distributed on the surface, in advance of the boat, calms the water, and as the oil drifts backward a smooth surface surrounds the boat. In this way the crew is enabled to row the boat over a belt of smooth surface although 65 bounded by surf and breakers on either side. By this means a distant wreck is easily and safely reached from the shore even in the roughest weather.

Referring now more particularly to Fig. 2, 75 which represents a larger craft, in this case discharge-pipes are led from the oil-tank to various parts of the ship, said pipes being provided with stop cocks, whereby the oil may be directed and discharged to windward in 80 whatever position the vessel may be. Thus the tank B is provided with the system of discharge-pipes b, f, g, h, i, k, and l, provided, respectively, with the stop-cocks or valves m, n, p, q, r, s, and t, whereby the oil may be directed to windward, as described, through any nozzle which happens to be to windward. E 85 is a portable spar carrying the discharge-pipe i, wholly or partly flexible. This spar is thrust out to windward from any part of the 90 vessel, thus carrying the nozzle of the discharge-pipe i outwardly, whereby the oil may be discharged upon the surface of the water at a considerable distance to windward of the vessel.

The spar E may be secured in position in any suitable manner. As shown here, however, the inner end is held in place by the brace u, and where said spar passes over the side of the vessel it is secured by the clasp or 95 hasp v.

It will be observed that the discharge-pipe may be carried down close to or even below the surface of the water, as may be found ad-

vantageous. Furthermore, any suitable form of discharge-nozzle may be used which may be found most advantageous under given circumstances.

5 Several styles of suitable nozzles are shown in Fig. 4, in which the nozzle *c* is contracted at its orifice *c'*, in order to discharge the oil in a solid forcible stream, which will reach its destination on the water and resist the tendency of the wind to blow it away. The nozzle *c* terminates in a flaring sprinkler, in order to discharge the oil in small streams, as if from a watering-pot. Various other forms of nozzle between these extremes may be used—
15 such, for instance, as nozzles having double or triple orifices situated some distance apart. These are matters of detail, any of which may be used in carrying out my invention.

It will be observed that when the stop-cocks 20 in the discharge-pipes are all closed the air-pump *C* may be worked to accumulate a heavy pressure of compressed air in the tank *B*, which, when one of the stop-cocks is opened, will cause the oil to flow, even after the pump has 25 ceased to work.

I do not herein claim anything shown and claimed in my Patent No. 335,035, dated January 26, 1886, on apparatus for distributing oil on troubled waters.

30 What I claim as my invention, and desire to secure by Letters Patent, is—

1. In an apparatus for distributing oil on the surface of troubled water, the combination, substantially as described, of a vessel, an air-pump and an oil-tank located on said vessel, an air-pipe leading from said air-pump and connected to said oil-tank, and a discharge-pipe leading from said oil-tank and adapted 35 to discharge oil on the surface of the water outside of said vessel, said oil being forced through
40

said discharge-pipe by the pressure of air forced into said tank by said air-pump, for the purpose set forth.

2. In an apparatus for distributing oil on the surface of rough water, the combination, 45 with the vessel *A*; of the air-pump *C* and the oil-tank *B*, located on said vessel, the air-pipe *a*, connecting said pump and tank, and the discharge-pipe *b*, leading from said oil-tank and adapted to discharge oil on the surface of 50 the water outside of said vessel, for the purpose of preventing the breaking of waves over the same, said discharge-pipe being provided with a stop-cock adapted to regulate the flow of oil through said pipe, and also to permit the 55 accumulation of air-pressure in said oil-tank when said stop-cock is closed, substantially as described.

3. In an oil-distributing apparatus on a vessel, the combination, substantially as described, 60 of the following elements: the air-pump, the oil tank or reservoir, the air-pipe connecting said air-pump and oil-tank, the discharge-pipe leading from said oil-tank, and the adjustable spar or boom supporting the outer end of said 65 discharge-pipe, and capable of being thrust outwardly from any desired portion of the vessel and there supported adjustably in place.

4. In a vessel provided with an oil-distributing apparatus, the portable boom or spar 70 *E*, capable of being thrust outwardly from any desired portion of the vessel and there supported adjustably in place, said spar carrying the flexible discharge-pipe *i*, substantially as and for the purpose set forth.

FRANCIS D. MONTAGUE.
